Atty.

UNITED STATES PATENT OFFICE.

CHARLES F. LITTLEJOHN, OF NEW HAVEN, CONNECTICUT.

CORSET, GIRDLE, AND THE LIKE.

Application filed September 15, 1925. Serial No. 56,424.

The present invention relates to corsets, girdles and the like and one object of the invention is to produce simple and efficient fastening means whereby adjustment may be easily effected. The invention is applicable to different types of corsets or girdles but it is particularly designed for corsets made of elastic material that are arranged to be fastened at the front.

10 It has previously been proposed to provide corsets of this type with means whereby adjustment thereof is obtained by fastening devices arranged in a plurality of parallel rows at the edge or edges of the corset and when adjustment is required, the same is effected by engagement of the fastening devices in the first, second or other row so that the desired tightness of fit can be obtained. In practice, it has however been 20 found to be a disadvantage when the two ends of the corset overlap and one of the purposes of the present invention is to eliminate that disadvantage.

According to the present invention, the 25 ends of the corset are provided with the usual stiffening stay or steel on which the clasps and studs or hooks and eyes or other preferred fastening means are carried. One part of the fastening device is secured to 30 one end of the corset and the corresponding part on the other end. It is now proposed to employ an intermediate separable section or member carrying at one side one part of the fastening means at one edge thereof and 35 on the other edge the other part of the fastening device is carried. The arrangement is such that this intermediate member or piece will serve as a link between the fastening devices fixed on the corset edges. By 40 such means, when the corset has become shaped or stretched to fit the form of the wearer, further adjustment can be obtained by dispensing with the intermediate part so that the fastening is effected directly by the 45 means carried at the ends of the corset.

The invention will be more fully described with reference to the accompanying drawing wherein—

Figure 1 is a fragmentary view showing a 50 part of the corset and the improved fastening means and

Figure 2 is a detail view showing a modified form of the intermediate piece or member.

55 Referring to the drawings, the embodi-

ment of the invention shown therein consists of a corset or girdle 1 having the ends 2 which are stitched in the usual way to provide pockets for the stiffening stays or steels 3. The latter carry the fastening devices 60 which in the present case consist of the clasps 4 and studs 5 and also at the upper end, the hooks 6 and the eyes 7. The latter devices are employed preferably for the upper end of the stays where more flexibility 65 is desirable. In the example shown in Figure 1, the intermediate member 8 is provided with clasps and studs 4' and 5', also hooks and eyes 6' and 7' and this piece or member 8 is covered with a suitable fabric. 70 The member 8 is composed of separate stays arranged parallel to each other and which are contained within a pocket or pockets formed by stitching said member along its length between said stays or at one edge if 75 the fastening devices permit of such stitching.

In the example illustrated by Figure 2, the separable or intermediate member 8 is composed of one piece having slotted ends 9 80 in order that the member may be more flexible to meet the demand for a corset which has more flexibility at the upper and lower ends. Furthermore, the member 8 in this modification need not be covered with fabric, 85 instead the same may be coated with a suitable elastic enamel.

It will be understood, after the corset or the like has been worn for a comparatively short time, the material of which the corset 90 is made is inclined to stretch and consequently adjustment is necessary to more closely fit the body of the wearer. To accomplish this adjustment the intermediate piece is bodily removed and since the said 95 member is in use only for a comparatively short time, it need not be constructed to stand long use therefore the cheapness of its production is a consideration. When the separable piece 8 is removed the corset ends 100 may be fastened directly by the devices thereon. The intermediate piece 8 may be composed of the same material as the stays, that is a thin gage of sheet steel or if desired said member may be composed of any 105 suitable material which will give the required stiffness to the front of the corset.

It will be understood that various modifications may be made which will come within the spirit of the present invention and it 110

is therefore intended that any modification coming fairly within the terms of the appended claims shall be covered thereby.

I claim—

- 5 1. In a corset or girdle as described, an intermediate separable member adapted to form a connection between the ends of the corset or girdle, said member being composed of flexible sheet material and said member having vertical open slotted ends whereby increased flexibility of said member at said ends is obtained.
- 10 2. In a corset or girdle as described, an

intermediate separable member adapted to form a connection between the ends of the 15 corset or girdle, said member being composed of flexible sheet material coated with an elastic enamel and said member having vertical open slotted ends whereby increased flexibility of said member at said ends is 20 obtained.

Signed at New Haven, county of New Haven, State of Connecticut, the 14th day of September, 1925.

CHARLES F. LITTLEJOHN.
